UNITED STATES PATENT OFFICE.

MARTIN FEYBUSCH, OF NEW YORK, N. Y., AND PAUL W. FLEISCHER, OF WEEHAWKEN, NEW JERSEY, ASSIGNEES TO NEW JERSEY MACHINE CORPORATION, OF HOBOKEN, NEW JERSEY, A CORPORATION OF NEW JERSEY.

SHEET-MOUNTING MACHINE.

Application filed April 28, 1923. Serial No. 635,229.

This invention relates to machines for mounting sheets, that is, for pasting large sheets of paper, such as lithographs and other pictures, linings and the like on cardboard sheets.

Considerable difficulties have been experienced in the operation of machines of this character, especially when the machine is intended for large output. If glue rolls of relatively small diameter could be used and glue of a liquid character, there would be no particular difficulty in obtaining an even coating of the sheets to be mounted. With glue rolls of relatively large diameter, however, as used in our machine, it has been found that the glue is not distributed on the glue-applying roll with sufficient evenness to insure an even and smooth coating of the sheet of paper passing through the machine. Especially when using relatively thick paste, as is desirable in machines of this character, it is difficult to obtain a sufficiently even distribution of the paste, the latter having a tendency to form beads or spots of uneven thickness which produce an unsightly appearance of the mounted sheets.

It is therefore the purpose of our present invention to provide a machine which will operate automatically to paste a large number of sheets in succession, and which will do this in a satisfactory manner. Another object of the invention is to provide means whereby the picture or other sheet will be mounted on the cardboard very accurately and without forming wrinkles or blisters. According to our invention we obtain the desired result of a perfectly even coating of the sheet by providing means whereby this coating, after it has been applied to the sheet and before the sheet is mounted on the cardboard or other backing, is smoothed out so as to remove any unevenness in such coating.

Another object of the invention relates to means for keeping the sheet under even tension during the sheet-applying operation. Still another object is to so arrange the paper and board feeding parts of the machine that they will cooperate in such a manner that the sheet will register properly with the board to which it is to be pasted. A further object is to provide simple adjusting means whereby the machine can readily be adapted to sheets and boards of varying widths and lengths. Still a further object is

to so construct the machine that the parts which require frequent cleaning, are made readily accessible and removable.

In a general way, our machine comprises two tables located at opposite ends of the machine and serving to support the sheets and boards respectively which are to be connected. These sheets and boards are fed into the machine one by one, by intermittently-operated feed mechanism. The sheet is taken up by continuously-driven feed mechanism and fed to a glue roller which provides it on one side with a coating of adhesive. The sheet then passes over a smoothing device which serves to smooth out any unevenness in the coating, whereupon it reaches the mounting rollers which mount it on the sheet of cardboard or other backing which is being fed into the machine. The mounted sheet then passes over a conveyor to a friction roller attachment which serves to remove any imperfections which may still be present in the mounted sheet.

The objects and advantages of our invention will appear fully from the description following hereinafter and the novelty will be pointed out in the appended claims.

In the accompanying drawings we have illustrated an example of our invention, without defining its limits. In these drawings,

Fig. 1 is a longitudinal section through the whole machine; Fig. 2 is an enlarged section of the main parts shown in Fig. 1; Fig. 3 is a side elevation; Fig. 4 is an end view looking toward the left in Fig. 3; Fig. 5 is a section on line 5—5 of Fig. 3; Fig. 6 is a section on line 6—6 of Fig. 5; Fig. 7 is a section on line 7—7 of Fig. 2; Figs. 8 and 9 are small detail views showing more clearly certain parts illustrated in Fig. 2, these sections being taken on lines 8—8 and 9—9 respectively of Fig. 7; Fig. 10 is an enlarged detail view of certain parts shown in Fig. 2; Fig. 11 is a detail view showing a conveyor part indicated in Fig. 2; and Fig. 12 is a partial plan view of one of the tables with its gauging devices.

The machine illustrated in the drawings comprises parallel frames 20, 20' and 21, 21' respectively, carrying at one end a table 22 serving as a support for the sheets to be mounted and at the other end a table 23 serving as a support for the boards on which

the sheets are to be mounted. Adjacent to the forward end of the table 22 are arranged two impeller rollers 24, 25 the upper one of which, 25, need not be continuous but 5 may consist of spaced, rubber-covered disks such as indicated at 25' in Fig. 7. On the side of the rollers 24, 25 opposite to the table 22 is arranged a support 26 (Fig. 2), and at the other end of this support are a pair of 10 feed rollers 27, 28, the upper one of which 28, is supported loosely in open-top slots of brackets 29 and rotates by frictional contact with the lower roller 27. On the other side of the rollers 27, 28 are located two 15 gumming rolls 30, 31, the lower one of which, 30, rotates in such a manner that a portion of its surface dips into a glue pan 32, and it transmits a coating of glue or other adhesive to the upper roll 31 which 20 coating is then communicated to the sheet passing over the roll 31. An L-shaped bar 33 carried by brackets 34 supported adjustably by means of set screws 35 serves to press the sheet into contact with the glue- 25 applying roll 31. The sheet is removed from the roll 31 by means of spaced pick-off fingers 36 mounted on a rod 37 resting in slots 38 of the machine frame and held in such slots by screws 39. Carried by the 30 fingers 36 are curved guide members 40 which serve to lead the sheet away from the roll 31, over a roller 41 and into contact with another roll, 42, a curved guide plate 43 serving to direct the sheet into contact 35 with the surface of the roller 42. While the sheet passes over the roller 41 with its gummed side facing away from the roller, it is reversed when passing over the roller 42, that is, the gummed side of the sheet faces 40 the roller and comes in contact therewith, with the result that any unevenness which may be present in the coating of adhesive will be smoothed or evened out. A wiper 43^a of felt or the like is arranged adjacent to 45 the roller 42 and in contact therewith; this wiper can be adjusted toward and from the roller by means of screws 44.

The sheet passing over the roller 42 is removed therefrom by pick-off fingers 45 similar to the fingers 36, carried by a rod 46 resting loosely in suitable slots of a frame part. The curved guides 47 on these fingers guide the sheet around a portion of a roller 48 which together with a roller 49 arranged 55 above the roller 48 serves to mount the sheet on a piece of cardboard or the like which has been brought into proper position by mechanism to be described further on. The roller 48 rotates in contact with a stationary wiper 50 covered with felt or the like and slidable toward and from said roller; springs 51 normally press the wiper against the roller. Set screws 52 hold the wiper against rotation but allow it to be adjusted around its axis in case of wear. The 60

roller 49, which is preferably rubber-covered, is carried in bearing boxes 53 (Figs. 2 and 10) slidable up-and-down in slots 54 formed between the frame parts 20, 21 and 20', 21' respectively. The bearings 53 are 70 normally pressed downward by springs 55 and the tension of the springs can be adjusted by means of screws 56 threaded into the bearings 53 and passing freely through stationary plates 57, the latter forming bearing 75 surfaces for the upper ends of the springs 55. The bearings 53 are provided with inwardly projecting lugs 53' (Fig. 10) engaged from below by the rounded ends of levers 58 pivoted at 58' on the frame parts 80 20', 21' respectively and carrying at their other ends rollers 59 adapted to be engaged by cams 60 mounted on a shaft 61. The rollers 59 are normally in the position Fig. 2 and are adapted to be depressed at times 85 by the cams 60 for the purpose of raising the roller 49 out of contact with the roller 48, as will be explained below. Screws 53' serve to adjust the position of the levers 58.

Mounted on the shaft 61 are disks 62 (Figs. 2 and 4) provided with a rubber covering having raised portions or pads 62' extending over part of their circumference. Arranged underneath the shaft 61 in a position to cooperate with said pads 62', is a 90 roller 63 the upper surface of which is approximately in alignment with the table 22. Between the roller 63 and the roller 48, in alignment with their upper surfaces, is arranged a support 64 similar to the support 26. 100 As shown in Figs. 2 and 3, the shaft 61 is mounted yieldingly, a spring 65 tending to press it toward the roller 63.

On the side of the rollers 48, 49 opposite to the table 64 are arranged L-shaped brackets 66 (Fig. 2) pivotally supported on the frame parts 20, 21 at 67 and normally held stationary by locking levers 68 (Figs. 2 and 3) also pivoted to said frame parts. Mounted between the brackets 66 is a roller 69 over 105 which extends an endless conveyor belt which may consist of spaced bands 70 of canvass or the like. These bands are held apart by spacing members 71 (Figs. 2 and 11) carried on a bar 72 extending rigidly between the free ends of the L-shaped brackets 66. The members 71 are adjustable not only lengthwise but also circumferentially of the bar 72 and may thus serve to adjust the tension of the individual conveyor bands. 115 Set screws 71' hold the members 71 in position after such adjustment.

The conveyor 70 passes over a roller 73 supported on a friction roller device indicated in Fig. 1 and comprising two sets of 120 rubber-covered rollers 74, 74' and 75, 75' driven by suitable gearing from a pulley 76. The roller 73 is driven by a gear 77 in mesh with the gear on the roller 74 and it is carried in brackets 78 adjustable about the axis 125 130

of the gear 77, a locking screw 78' serving to secure the brackets in position. By changing the position of the brackets 78, the tension of the conveyor belt as a whole 5 can be varied.

The rollers 27, 30, 31, 41, 42, 48 and 49 are driven continuously in the following manner (Figs. 3 and 4): Between the frame parts 20, 21 is arranged a main shaft 79 10 driven by means of a pulley 80 and provided with a hand wheel 81. This shaft carries a gear 82 in mesh with an idler gear 83 meshing with a pinion 84 on the feed roller 27. The gear 83 also engages a gear 85 15 on the shaft of the upper glue roller 31. On this shaft are mounted a gear 86 meshing with a gear 87 on the lower glue roller 30 and a gear 88 meshing with a pinion 89 with which is rigidly connected a pinion 90 20 in mesh with a pinion 91 mounted on the shaft of the roller 42. Another pinion, 92, also rigid on this shaft, meshes with a pinion 93 on the shaft of the roller 48, and on the other side of the machine this roller carries 25 a pinion 94 in mesh with a pinion 94' on the shaft of the roller 49. The roller 41 is driven from the roller 42 by gearing 95, 96 (Fig. 4).

The feed-in or impeller rollers 24, 25 and 30 62, 63 are operated intermittently, that is, whenever a new sheet and a new board are to be introduced into the machine. The mechanism for effecting this intermittent operation is as follows (Figs. 2, 3, 5, 6 and 7): 35 On a transverse shaft 97 located underneath the rollers 24, 25 is mounted a gear 98 meshing with the gear 82 on the main shaft 79 and therefore driven continuously. Interposed between the gear 98 and the shaft 97 40 is a sleeve 99 provided with radially-extending recesses 100 in which are located clutch members such as rollers 101 engaging recessed or flattened portions 97' of the shaft 97 (Figs. 5 and 6). The hub of the gear 98 is provided with radial slots 98' in which are located friction plugs 102 engaging with their inner surfaces the outer surface of the sleeve 99: these friction plugs are held in 45 position by an annular coiled spring 103. A collar 104 rigid on the shaft 97 serves to prevent lateral movement of the gear 98. The sleeve 99 is provided with a projecting lug 105 engaged at times by one end of a two-armed lever 106 (Figs. 3, 5 and 6) fulcrumed on the frame at 107. The lever 106 50 is held in engagement with the lug 105 by a spring 108 and can be swung to a position in which it releases the lug by depressing the handle 109 or the treadle 110, which latter 55 is connected with the lever 106 by a rod 111. On the shaft 97 is also mounted, rigidly, on the other side of the machine, a mutilated gear 112 (Figs. 2, 7 and 8) whose teeth 60 are in mesh with a pinion 113 on the roller 24, this pinion also meshing with a pinion

114 on the roller 25. At the portion of its circumference where there are no teeth, the mutilated gear 112 is provided with a smooth, projecting ledge 112' cooperating with the concave portion of a locking disk 70 115 rigid with the pinion 113, to prevent rotation of the latter while it is not engaged by the teeth of the gear 112. In order to bring the teeth of the pinion 113 into engagement with the first teeth of the gear 112, the latter is provided with a roller 116 75 cooperating with a starting lug 117 rigid with the pinion 113. With this construction it will be seen that the roller 24 rotates as long as the pinion 113 is in mesh with the teeth of the mutilated gear 112, and that it is held stationary during the time that the gear 112 rotates with its ledge 112' engaging the locking disk 115. The roller 25 with its pinion 114 is movable up and down relatively to the roller 24, and for this purpose the roller 25 is supported in arms 118 fulcrumed at 119, springs 120 tending to hold the upper ends of said arms in engagement with adjusting screws 121 screwed into the upper ends of levers 122 rigid on short rocking shafts 123. Secured rigidly to one of the rock shafts 123 is a lever 124 pivotally connected with the upper end of a slide 125 (Fig. 9) guided in its movement on the shaft 97 and carrying at its lower end a roller 126 actuated by a cam 127 held to rotate with the shaft 97. The springs 120 tend to hold the roller 126 in engagement with the cam 127. On the shaft 97 is also mounted a 100 sprocket 128 (Figs. 4 and 7) which by means of a chain 129 drives a sprocket 130 on the roller shaft 63, on which roller shaft is mounted a pinion 131 meshing with a gear 132 on the roller shaft 61 (Figs. 2 and 4). 105

Arranged in the pulley 80 is a friction clutch 133 (Fig. 4) actuated by a spring 134 to couple the shaft 79 with the pulley 80. The clutch 133 has a sleeve 135 engaged by a forked lever 136 fulcrumed at 137 and 110 connected with its other end to a rod 138 which in turn is connected by a link 139 to a rock shaft 140 (Figs. 3 and 4) held in bearings 141 and provided with handles 142. By operating one of these handles, the shaft 140 can be turned, thus disconnecting the clutch 133 from the pulley 80, against the tension of the spring 134. 115

To lock the shaft 140 in a position in which the clutch 133 disconnects the shaft 120 79 from the pulley 80, one of the handles 142 may be provided with a socket 142' (Fig. 3) cooperating with a projection 143 on the adjacent bearing 141, a spring 144 tending to keep the projection 143 and the 125 socket 142' in engagement. By pushing the shaft 140 lengthwise of its axis, against the tension of the spring 144, the projection 143 will become disengaged from the socket 142', thus allowing the shaft 140 to be turned. 130

The lower glue roll 30 is not mounted rigidly, but yieldingly and adjustably with respect to the upper glue roll 31. It is supported in brackets 145 pivoted at 146 and 5 pressed upward by springs 147, the pressure of the lower roll against the upper roll being adjustable by means of screws 148, (Figs. 2, 3 and 4). The glue pan 32 is carried by brackets 149 movable up and 10 down by means of a lever 150 fulcrumed at 151, a link 152 and crank 153 connecting the brackets and the fulcrum rod 151. A pin 154 engaging one or the other of a series of sockets 155 in the machine frame serves to 15 arrest the glue pan in any desired position. The brackets 149 are forked at their lower ends (Fig. 3), these forks fitting over the rod 151 and serving, in conjunction with lugs 156 on the frame (Fig. 2), to guide the 20 brackets in their up-and-down movement.

In order to properly position the sheet and the board on their respective tables 22 and 23, these tables are provided with gauges which have been illustrated in Figs. 3 and 25 12 in connection with the table 23. These gauging devices comprise a side gauge 157 adjustable transversely of the table by means of slots 158 and screws 159, and an end gauge 160 adjustable lengthwise of the table 30 by means of slots 161 and screws 162. For the purpose of affording adjustment over a wider range than the slots 158 and 161 permit, the table as well as the side gauges 157 are provided with sockets 163, 164 respectively. By simply shifting the screws 159 or 162 to another socket, such wider adjustment is obtained. It is to be understood that the table 22 is provided with gauges similar to those just described in 40 connection with the table 23.

The operation of the sheet-mounting machine is as follows: First a sheet S to be mounted and a board B on which the sheet is to be mounted, are placed in position on 45 their respective tables 22 and 23, with their backs and one of their sides against the gauges. The roller 25 at this time is raised out of contact with the roller 24, so that the forward end of the sheet can be introduced between these two rollers, and similarly the forward edge of the board can be introduced between the rollers 62, 63. If then the friction clutch 133 is thrown in, connecting the shaft 79 with the pulley 80, 50 all the rollers will be set in motion with the exception of the impeller rollers 24, 25 and 62, 63. In order to set these impeller rollers into motion, it is necessary to depress the handle 109 or the treadle 110 (Fig. 60 3). This will release the projection 105 from the lever 106, allowing the friction plugs 102 to take along the sleeve 99 (Figs. 5 and 6), this movement displacing the sleeve 99 slightly relatively to the shaft 97 and 65 causing the friction rollers 101 to couple the shaft 97 with the gear 98, which latter rotates continuously. The movement of the shaft 97 will be communicated to the impeller rollers 24, 25 as soon as the pinion on the roller 24 comes in contact with the 70 teeth of the mutilated gear 112 (Figs. 2, 7 and 8), the upper roller 25 having in the meantime been brought down toward the lower roller 24 by the action of the cam 127 and spring 120. The sheet S, which 75 had previously been placed between the rollers 24, 25, as described above, is thus fed into the machine, over the support 26, into contact with the feed rollers 27, 28. The sheet is seized by these rollers and passes 80 under the guide 33 to the upper glue roll 31 which provides it on one side with a coating of adhesive. As soon as the forward end of the sheet S has reached a point between the rollers 27, 28, the feeding action 85 of the impeller rollers 24, 25 is interrupted owing to the action of the cam 127 which lifts the roller 25 out of contact with the roller 24. Notwithstanding the fact that the roller 24 may continue to rotate until 90 its pinion 113 reaches the end of the teeth of the mutilated gear 112, there is no positive feeding action by the impeller rollers, the feeding-in of the sheet S being now done entirely by the feed rollers 27, 28. 95

In the meantime, the lever 106 has been allowed to return to its original position, in the path of the projection 105 on the sleeve 99 (Fig. 6). As soon as the projection 105 comes in contact with the lever 106, the 100 sleeve 99 will be arrested. The shaft 97 has a tendency to continue its rotation, displacing itself relatively to the sleeve 99, and this displacement will interrupt the frictional engagement between the rollers 101, the gear 105 101 and the shaft 97, thus bringing the latter to a stop. The impeller roller 24 will therefore be arrested and will not resume its motion until the handle 109 or treadle 110 are again depressed, which will be done only 110 after a new sheet has been placed in position for mounting.

The sheet which has been coated on one side with adhesive, as described above, is removed from the roll 31 by the pick-off 115 fingers 36 (Fig. 2) and guided by the guide fingers 40 over the roller 41 into contact with the roller 42, with the coated surface facing the roller. It will be noted that the gears 90, 91 (see Fig. 3) which serve to 120 drive the roller 42 are so proportioned that the roller 42 will rotate at a greater angular speed than the roller 41, and as the roller 42 is also the larger in diameter, its periphery travels faster than that of the roller 41 thereby not only effecting a wiping action 125 upon the freshly coated sheet but also causing sufficient tension to be placed upon the sheet to maintain it in a smooth unwrinkled condition. This roller 42 is of great im- 130

- portance in our machine, since it serves in conjunction with the rollers 41 and 48, to place the sheet under a double flexure which assists in maintaining the sheet under tension in such a way that the roller 42 will smooth out any unevenness which may be present in the coating of adhesive and which would produce unsightly places and spots in the finished mounting. The sheet is then 10 moved from contact with the roller 42 by the pick-off fingers 45 and guided around the roller 48 to the upper portion thereof by the guide members 47. It will be evident from an inspection of Figs. 2 and 3 15 that the linear speed of the peripheries of the rollers 48 and 49 is the same as that of the roller 42, therefore the tension placed upon the sheet is maintained until it is mounted.
- 20 During the rotation of the shaft 97 the roller shaft 61 has also been rotated by means of the sprockets 128, 130 and the chain 129. The operation of the two shafts is so timed that when the sheet S reaches the 25 upper portion of the roller 48, as just described, the forward edge of the board B will have been fed by the feeding disks 62 to the same point. The sheet S and the board B will then pass together, that is, in 30 contact with each other, between the rollers 48, 49 which will press them together, and the sheet will thus be mounted on the board. In order to prevent the glue from being 35 squeezed out at the forward edge of the sheet, the pressure between the two rollers 48, 49 is relieved for a short moment by the cam 60, this latter lifting the roller 49 slightly away from the roller 48.
- After passing between the rollers 48, 49, 40 the mounted sheet is then taken over the conveyor 70 to the friction roller device, where it passes between the sets of rollers 74, 74' and 75, 75'. It will be noted that the members of each set of rollers are of different diameters, the lower rollers 74 being 45 smaller than the upper rollers 74', while the lower rollers 75 are larger than the upper rollers 75', thus producing a slight flexure of the mounted board as it passes between 50 each pair of rollers, which flexures are opposite in direction due to the reversal of the positions of the larger and smaller rollers. This double flexure will have the effect of 55 smoothing out any imperfections which may still be present in the mounted sheet.
- Should the board and the sheet not register properly, or in other words, should either the board or the sheet reach the point of connection either too soon or too late, this 60 can be remedied readily by simply shifting one or the other of the end gauges 160 toward or away from the machine.
- In a machine of this character it is very 65 desirable that all the operating parts, and especially the rollers, be readily accessible for the purpose of inspecting, cleaning, or exchanging them. To obtain this result, each of the two machine frames has been made in two parts, one of which is movable relatively to each other. The movable frame 70 parts 20', 21' are hinged to the fixed frame part (20 and 21 respectively) at 165 (Figs. 2 and 3), the parts being normally held together by locking arms 166 fulcrumed at 75 58' and having suitable recesses fitting over pins or screws 167. After unlocking the levers 166, the frame parts 20', 21' with the parts carried thereby can be swung from the position shown in full lines in Fig. 2 to that indicated in dotted lines, and the various 80 rollers held in their bearings on the frame parts 20, 21 will be exposed and readily accessible. For the purpose of rendering these parts still more accessible, the portion of the table 23 adjacent to the machine is 85 also made movable by being hinged to the remainder of the table as shown at 168 in Figs. 3 and 12. The left-hand end of the hinged table portion is supported on a rod 169 extending between the frame parts 20', 90 21'. In order to swing the movable table portion to the position shown in dotted lines in Fig. 3, it is necessary to first remove the supporting rod 169, whereupon the table can be swung to such position, as will be clear 95 from Figs. 2 and 3.
- In order to render such machine parts as the roller 41 and the wiper 50 accessible, the right-hand end of the conveyor 70 is mounted movably, that is, it can be swung 100 out of the way (Figs. 2 and 3). The locking levers 68 have recesses fitting over the bar 72, thus normally locking the conveyor in its operative position shown in full lines in Fig. 2. To bring the conveyor 70 to its inoperative position, it is released from the locking levers or latches 68, whereupon it can be 105 swung up on its pivots 67 and brought to rest on notches or depressions 68' formed in the end surfaces of the latches 68, as shown 110 in dotted lines in Fig. 2.
- Various modifications may be made without departing from the nature of our invention as set forth in the appended claims. 115
- We claim:
1. A machine for mounting sheets on boards, comprising mechanism for coating a sheet with adhesive, mechanism for mounting said sheet on a board, continuously-operated mechanism for feeding said sheet to said coating mechanism, intermittently-operated mechanism for feeding said sheet to said continuously-operated feed mechanism, and means for interrupting the feeding operation of the last-named mechanism at a 120 predetermined moment.
  2. In a machine for mounting sheets on boards, parallel frames each having portions movable relatively to the remainder of the frames, and mounting mechanism so ar- 125

- 6 ranged as to be readily accessible when said movable frame portions are separated from the remainder of the frames.
3. A machine for mounting sheets on boards, comprising a pair of supports, one for a board and one for a sheet, a pair of feeding rolls adjacent to one of said supports, a second pair of feeding rolls adjacent to the other of said supports, means interposed between said supports for coating with adhesive one side of said sheets, an intermittent gearing for actuating said first named pair of rolls, and connections from said intermittent gearing for driving said second pair of rolls in timed relationship with said first named pair of rolls.
4. A machine for mounting sheets upon boards, comprising a pair of pressure rolls, a support for a board adjacent to said pressure rolls, a pair of feeding rolls for feeding a board from said support to said pressure rolls, a gumming roll, a second support for sheets mounted on said machine at a distance from said board support, a second pair of feeding rolls for feeding sheets from said second support to said gumming roll, and a plurality of rollers interposed between said gumming and pressure rolls for feeding the gummed sheet to said pressure rolls, means for driving said pairs of feeding rolls intermittently and for causing said first pair of feeding rolls to be operative a predetermined time interval after the operation of said second pair of feeding rolls.
35. 5. A machine for mounting sheets upon boards, comprising a pair of pressure rolls, a gumming roll, means for feeding a sheet to said gumming roll, and means interposed between said pressure rolls and said gumming roll, for transferring the gummed sheet from said gumming roll to said pressure rolls, said means including a spreading roll rotating at a greater speed than said gumming roll and engaging the gummed side of said sheet to spread the adhesive evenly thereon.
6. A machine for mounting sheets upon boards, comprising a pair of pressure rolls, a support for a board adjacent to said pressure rolls, a pair of feeding rolls for feeding a board from said support to said pressure rolls, a gumming roll, a second support for sheets mounted on said machine at a distance from said board support, a second pair of feeding rolls for feeding sheets from said second support to said gumming roll, a plurality of rollers interposed between said gumming and pressure rolls for feeding the gummed sheet to said pressure rolls, and means for driving said plurality of rollers at a greater speed than said gumming roll to maintain tension upon said gummed sheet in its passage from said gumming roll to said pressure rolls.
65. 7. A machine for mounting sheets upon boards, comprising a pair of pressure rollers, a pair of feeding rolls adjacent to said pressure rollers for feeding the boards thereto, a gumming roll, a second pair of feeding rolls to feed the sheets to be mounted to said gumming roll, means for driving said pairs of feeding rolls intermittently, and means actuated thereby for momentarily releasing the pressure between said pressure rolls as the sheets and boards are engaged thereby.
8. A machine for mounting sheets upon boards, comprising a pair of pressure rollers, a gumming roll, a pair of feeding rollers for feeding the boards directly to said pressure rollers, a second pair of feeding rollers for feeding the sheets directly to said gumming roll, and means for transferring the gummed sheet from said gumming roll to said pressure rollers, including a transfer roll, a spreading roll, and plurality of curved guiding members to direct the sheets into contacting engagement with said transferring means.
9. A machine for mounting sheets upon boards, comprising a pair of pressure rolls, a gumming roll, a pair of feeding rolls for feeding the boards to the pressure rolls, a second pair of feeding rolls to feed the sheets to the gumming roll, means for driving said feeding rolls intermittently and in predetermined timed relationship, and means actuated thereby for momentarily moving the members of each pair of feeding rolls out of contacting engagement to permit the sheets and board to be inserted readily between said feeding rolls.
10. A machine for mounting sheets upon boards, comprising a pair of pressure rolls, a gumming roll, a pair of feeding rolls for feeding the boards to the pressure rolls, a second pair of feeding rolls to feed the sheets to the gumming roll, resilient means to hold said feeding rolls normally in contacting engagement, means for driving said feeding rolls intermittently and in predetermined timed relationship, and means actuated thereby for momentarily moving the members of each pair of feeding rolls out of contacting engagement to permit the sheets and board to be inserted readily between said feeding rolls.
11. A machine for mounting sheets upon boards, comprising a pair of pressure rolls, a gumming roll, a pair of feeding rolls for feeding the boards to the pressure rolls, a second pair of feeding rolls to feed the sheets to the gumming roll, resilient means for holding each of said pair of feeding rolls and said pressure rolls normally in contacting engagement, intermittent means for driving said feeding rolls and means actuated thereby for momentarily moving the members of said first pair of feeding rolls, said second pair of feeding rolls, and said pair of pressure rolls out of contacting engagement suc-

cessively and in predetermined timed relationship in the order named.

12. In a machine for mounting sheets upon boards, a gumming device for applying a coating of adhesive to the sheets, a pair of pressure rolls for pressing the gummed sheets upon the boards, a roller interposed between said pressure rolls and said gumming device to transfer the gummed sheet from said gumming device to said pressure rolls, to smooth the coating of adhesive upon said sheet and to exert a tension upon said sheet and maintain it in a smooth unwrinkled condition in its passage from said gumming device to said pressure rolls.

13. In a machine for mounting sheets upon boards, a gumming device for coating a sheet with adhesive, pressure means for mounting the coated sheet upon a board, and mechanism for smoothing the mounted board, comprising two juxtaposed pairs of smoothing rolls, the members of each pair of smoothing rolls being of different diameters arranged oppositely in each respective pair to exert a double flexure upon said mounted board as it passes through said mechanism.

14. In a machine for mounting sheets upon boards, a gumming roll for applying a coating of adhesive to the sheets, a pressure device for mounting the gummed sheets upon the boards, and means for transferring the gummed sheet from the gumming roll to the pressure device, said means comprising a smoothing roll to engage the coated side of the sheet and a guiding means located upon opposite sides of the axis of said smoothing roll to place the sheet under a double flexure as it passes said smoothing roll.

15. In a machine for mounting sheets upon boards, a gumming roll for applying a coating of adhesive to the sheets, a pressure device for mounting the gummed sheets upon the boards, and means for transferring the gummed sheet from the gumming roll to the pressure device, said means comprising a plurality of rollers arranged to place the sheet under a double flexure as it passes from said gumming roll to said pressure device, one of said plurality of rollers engaging the coated side of said sheet to smooth the adhesive thereon.

16. In a machine for mounting sheets upon boards, a gumming roll for applying a coating of adhesive to the sheets, a pres-

sure device for mounting the gummed sheets upon the boards, and means for transferring the gummed sheet from the gumming roll to the pressure device, said means comprising a plurality of rollers arranged to place the sheet under a double flexure as it passes from said gumming roll to said pressure device, one of said plurality of rollers engaging the coated side of said sheet to smooth the adhesive thereon, and means for rotating said rollers at a greater speed than said gumming roll.

17. In a machine for mounting sheets upon boards, a gumming roll for applying a coating of adhesive to the sheets, a pressure device for mounting the gummed sheets upon the boards, and means for transferring the gummed sheet from the gumming roll to the pressure device, said means comprising a smoothing roll and a reversing roller to direct the coated side of said sheet into contact with said smoothing roll.

18. In a machine for mounting sheets upon boards, a gumming roll, a pair of feeding rollers for feeding the sheets to said gumming roll, one of said rollers being mounted for movement towards and away from the other, intermittently rotating means for said feeding rollers, and means operating in timed relationship therewith to cause said feed rollers to be brought into contacting engagement with the sheets during the dwell period of said intermittently rotating means, whereby the sheet will be clamped between said feed rollers before said rollers are rotated.

19. In a machine for mounting sheets upon boards, a gumming roll, a pair of feeding rollers for feeding the sheets to said gumming roll, one of said rollers being mounted for movement towards and away from the other, intermittently rotating means for said feeding rollers, and means operating in timed relationship therewith to cause said feed rollers to be held momentarily away from each other and then to be brought towards each other into contacting engagement with the sheet during the dwell period of said intermittently rotating means, whereby the sheet may be introduced between and then clamped by said feed rollers before said rollers are rotated.

In testimony whereof we have signed this specification.

MARTIN FEYBUSCH.
PAUL W. FLEISCHER.
